UNITED STATES PATENT OFFICE.

CHARLES J. TAYLOR, OF SHELBYVILLE, ILLINOIS.

COIN-CHUTE.

SPECIFICATION forming part of Letters Patent No. 611,530, dated September 27, 1898.

Application filed April 29, 1898. Serial No. 679,259. (No model.)

To all whom it may concern:

Be it known that I, CHARLES J. TAYLOR, of Shelbyville, in the county of Shelby and State of Illinois, have invented a new and Improved 5 Coin-Chute, of which the following is a full, clear, and exact description.

This invention relates particularly to coin-chutes designed to be used in connection with telephones at pay-stations; and the object is 10 to provide a device of this character that shall be simple in its construction, comparatively cheap to manufacture, compact, and easily attached to or detached from an ordinary telephone.

15 I will describe a coin-chute embodying my invention, and then point out the novel features in the appended claim.

Reference is to be had to the accompanying drawings, forming a part of this specification, 20 in which similar characters of reference indicate corresponding parts in all the views.

Figure 1 is a front view of a telephone with a portion broken away to show my invention as applied. Fig. 2 is an inside view of the 25 coin-chute, showing the parts in one position. Fig. 3 is an inside view showing the parts in another position. Fig. 4 is a section on the line 4 4 of Fig. 3, and Fig. 5 is a section through the line 5 5 of Fig. 1.

30 Referring to the drawings, 1 designates a casing, through the chute 2 of which a coin is designed to pass. On one wall 3 of this chute is a fixed stop 4, and below the fixed stop 4 is another fixed stop 5. Movable vertically in the chute, at the opposite side, is a plate 6, having near its upper end a stop 7 and near its lower end a stop 8. These several stops are inclined downward and inward on their inner edges.

40 Extended from the plate 6 through a slot in the casing is a pin 9, connected to an operating-lever 10, which in this case is the telephone-receiver-holding lever, and to this lever one end of a spring 11 is attached, the 45 other or upper end of said spring being attached to the telephone-casing. The stop 8 is in electrical connection with the talking-circuit wire 12, and the stop 5 is in electrical connection with the talking-circuit wire 13, 50 and it is designed that a coin by engaging with the stops 5 and 8 shall close the talking-circuit.

The device may be placed in a box arranged near or at the side of the telephone, or, as shown in the drawings, it may be placed with- 55 in the telephone-casing, in which event a coin-tube 14 leads from the upper end of the coin-chute out through the door or wall of the telephone-casing. The opening 15, through which the coin is to be inserted, may be made 60 for any-sized coin; but the device can only be operated by the coin intended, as said opening is just large enough to allow the desired coin to pass through it, and therefore too small to allow the entrance of larger coins. 65 When a coin smaller than that intended is inserted, it will fall through without closing the circuit.

The operation is as follows: Fig. 2 shows the normal position of the parts—that is, when 70 the telephone-receiver is hung on the lever or hook 10 the said lever will be held in its downward position against the resistance of the spring 11. At this time the salient points of the stops 4 and 7 will be directly opposite 75 each other, and the distance between these points is somewhat less than the diameter of the coin. The salient points of the stops 5 and 8, however, will be one lower than the other. After calling up the station or person 80 desired the calling party will drop a coin through the opening 15, and this coin will be engaged and held by the stops 4 and 7, as shown in Fig. 2. Then upon removing the receiver from its hook or lever the spring 11 85 will move said lever upward, and consequently shift the plate 6 upward, bringing the salient point of the stop 7 above the salient point of the stop 4, thus widening the distance between the stops and allowing the 90 coin to engage with the stops 5 and 8, which are now directly opposite each other. While in this position the coin closes the talking-circuit. After finishing the conversation the hanging of the receiver on its hook or lever 95 will move the parts to the normal position, widening the space between the stops 5 and 8 to allow the coin to drop into a suitable receptacle, and at this time the circuit is of course broken.

100 It is obvious that the stops 4 7 will prevent the falling through of a coin deposited before the receiver is removed from the hook, and therefore these stops provide additional

safety or assurance that the coin will ultimately perform its function as a circuit-closer. The stops 4 7 are of no particular use when a coin is deposited after removing 5 the receiver from the hook, as in such event the stops 5 8 will stop and hold the coin until the receiver is returned to the hook.

It is obvious that the stops 4 and 5 must be insulated one from the other. The inclining 10 of the stops, as shown, adapts the device for the varying sizes between new and worn coin of the required denomination.

Having thus described my invention, I 15 claim as new and desire to secure by Letters Patent—

A coin-chute, comprising a casing, fixed stops in said casing at one side, one above the other and insulated one from the other,

a vertically-moving plate at the opposite side of the casing, two stops on said plate, one 20 above the other, the two lower stops being in an electric circuit designed to be closed by a coin engaging with the lower stops, and a lever having connection with the movable plate, the movable stops being so related to the 25 fixed stops that when the lever is held downward the two upper stops will retain a coin, and when the lever is raised the coin will be released from the upper stops and caught and held by the two lower stops until the lever is 30 moved downward releasing the coin from the lower stops, substantially as specified.

CHARLES J. TAYLOR.
